SIDECAR ATTACHMENT FOR BICYCLES

Stanley L. Glamb, Wayne, Mich., assignor to Dual
Remote Control Co., Inc., Wayne, Mich., a cor-
poration of Michigan

Application August 25, 1947, Serial No. 141,039

Term of patent 14 years

(Cl. D34—15)

To all whom it may concern:

Be it known that I, Stanley L. Glamb, a citizen of the United States of America, residing in the county of Wayne and State of Michigan, have invented a new, original, and ornamental Design for a Sidecar Attachment for Bicycles, of which the following is a specification, reference being had therein to the accompanying drawing, forming a part thereof, wherein the single figure in the drawing is a perspective view of a sidecar attachment for bicycles, showing my new design.

The dotted showing is for illustrative purposes only.

I claim:

The ornamental design for a sidecar attach-
ment for bicycles, substantially as shown and
described.

STANLEY L. GLAMB.
